UNITED STATES PATENT OFFICE.

JOHN KARITZKY, OF GARWOOD, NEW JERSEY, ASSIGNOR, BY MESNE ASSIGNMENTS, TO HENRY E. NEWHALL CORPORATION, OF GARWOOD, NEW JERSEY, A CORPORATION OF NEW JERSEY.

NAIL EXPANSION.

Original application filed August 20, 1926, Serial No. 130,387. Divided and this application filed February 10, 1927. Serial No. 167,081.

This application is a division of my co-pending application Ser. No. 130,387, filed August 20, 1926.

My invention relates to expansion bolts 5 and more particularly to a nail expansion shield formed of wire, or similar material, the wire being either round, flat or any other form, and an insert of any suitable material.

My invention relates to such a wire shield 10 having a metal insert which serves to reduce the area of the axial bore, and to fill up, more or less, the intervals or spaces between the strands of the wire shield, to more readily guide the expanding member, and 15 increase the bond or grip of the shield with a support.

My invention further relates to a plurality of wire units held together by the insert.

My invention further relates to certain articles of manufacture and combinations 20 which will be more fully hereinafter described and pointed out in the claims.

In the accompanying drawings the same reference numerals refer to similar parts in 25 the several figures.

Fig. 1 is a perspective view of a wire unit, a plurality of which are used to make a wire shield;

Fig. 2 is a side elevation of one form of 30 wire shield formed by two of the units shown in Fig. 1, the units being held together by the insert;

Fig. 3 is a horizontal section on line 3—3 of Fig. 2;

Fig. 4 is a vertical section through a support showing a nail being inserted into the 35 shield;

Fig. 5 is a vertical section on the line 5—5 of Fig. 4 looking in the direction of the 40 arrows;

Fig. 6 is a horizontal section on the line 6—6 of Fig. 4;

Fig. 7 is a vertical section, similar to Fig. 4, showing the nail driven home in the 45 shield;

Fig. 8 is a vertical section on the line 8—8 of Fig. 7.

In my invention a cheap grade of commercial soft wire 1, of any suitable contour, is 50 cut to the particular length desired to form the integral wire units 2, having the longitudinally extending strands 3 and 4. A portion of the wire is bent at an angle to the strands to form the head portion 5, the ends

of the strands 3 and 4 are bent at substantially right angles to form the feet 6, 6 which not only are adapted to bite into the wall or other support in which the units are mounted but also assist in holding the metal 55 insert on the units.

My wire shield 7 is formed of a plurality of wire units 2 (Fig. 1), two such units being preferably employed, which are held together by the metal insert 8. This insert 60 not only serves as a guide for the nail 9, but reduces the area of the axial bore 10, so as to increase the expansion of the wire shield 7 at the end of the shield. The metal insert may hold the units together in various ways. I

have shown one way in which the metal insert 65 is formed out of a strip of sheet metal, or other suitable material, and wrapped around the strands 3 and 4 of the units 2, as shown very clearly in Fig. 3. It will be

clear from this figure that the metal insert 70 75 8 serves to close the gaps between the strands of the wire shield 7 and also forms a guide for the nail 9 so that the nail cannot be driven at an angle to the longitudinal axis of

the shield.

In use the shield is mounted in a hole 110 in a wall 11 and supports any suitable work, such as a bracket 12. As the nail 9 is driven into the shield, the different units 2, 2 will be forced apart, which action will be resisted 85 by the metal insert 8, which will become distorted (Fig. 8) or possibly broken as the nail is driven home. It will also be noted that the maximum expansion occurs at the inner

end of the wire shield removed from the face 90 95 13 of wall 11 so that the face of the wall will not be cracked or broken by the expansion of the shield.

While I have shown a smooth nail, it is to be understood that the nail may be provided with a roughened surface, and that a threaded bolt provided with square or counter sunk head may be employed instead of a nail. It

will be noted that my wire expansion shield 100 may be made at minimum cost, that it is simple and will give the maximum efficiency for a given size shield. It is further to be

noted that the different wire units are each open constructions, which will freely allow galvanizing by the hot process. The inserts 105 are preferably assembled with the units after the wire units have been galvanized though they may be assembled prior to gal-

vanizing, in which case the units and inserts will be galvanized together.

Having thus described this invention in connection with illustrative embodiments thereof, to the details of which I do not desire to be limited, what is claimed as new and what is desired to secure by Letters Patent is set forth in the appended claims.

What I claim is:—

- 10 1. A new article of manufacture comprising an expansion shield formed of a plural-

ity of wire units and an insert securing the units together, the units being provided with one or more feet adapted to grip the walls of a hole.

15 2. A new article of manufacture comprising a wire shield formed of a plurality of wire units, each unit being provided with a head member and with one or more feet, and an insert securing the units together.

JOHN KARITZKY.
